ABSTRACT OF THE DISCLOSURE

Apparatus for marking a moving continuous web for connection with a segmenting system including a rotatable segmenting wheel engaging said web for defining a plurality of segments in said web, said apparatus including a marking means having a rotatable die wheel engaging said web for marking same and operably connected to the means for driving said segmenting wheel for rotation thereby at a circumferential speed substantially equal to the circumferential speed of said segmenting wheel. The die wheel is removably mounted on the frame of the marking means for substitution of a die wheel selected from a group of die wheels of different diameters, adjustment means being provided for laterally displacing the impression roller, well and doctor means of said marking means relative to the longitudinal axis of said die wheel to accommodate said die wheels.

BACKGROUND OF THE INVENTION

This invention relates generally to arrangements for printing indicia on moving continuous webs which are then divided into a plurality of segments by a segmenting means such as a strip packaging system or a rotary knife system. The indicia imparted on the web must be in registration with the segments. Such registration has proved difficult to achieve, especially where the segmenting means is stopped and restarted in the middle of a run or the speed thereof is varied during a run. Still a further problem arises where a single segmenting means is used to produce different sized segments in a web such as by substituting sealing wheels of different diameters in strip packaging systems or rotary blade wheels of different diameters in rotary knife systems. Registration between the known web marking apparatus and the modified segmenting means requires modification of the former, such as by substitution of a new die wheel having the indicia spaced thereon in a predetermined but different pattern and adjustment of the speed of rotation thereof. In such known web marking apparatus the substitution of a new die wheel is a laborious task since the impression wheel is generally disposed above said die wheel and a great deal of the device must be dismantled to reach the die wheel.

SUMMARY OF THE INVENTION

Generally speaking, in accordance with the invention, an apparatus is provided for marking a moving continuous web, said web to be operated on by segmenting means for defining a plurality of segments in said web, including marking means having a rotatable wheel for marking said moving web and connecting means operably connecting the means for driving said segmenting means and said die wheel for rotating said die wheel at a circumferential speed substantially equal to the circumferential speed of the segmenting wheel of said segmenting means. Said die wheel and segmenting wheel are preferably rotated at substantially the same angular velocity and are of substantially identical diameters.

The marking means includes a frame, said die wheel

2

being removably mounted on said frame for substitution of a die wheel selected from a group of die wheels of different diameters. The impression roller is rotatably mounted on said frame on the side of said die wheel to permit the removal of said die wheel in an upwardly direction, said web passing in a substantially vertical direction between said impression roller and said die wheel.

Said marking means also preferably includes a well for carrying ink, said die wheel extending within said well for inking the peripheral surface thereof and doctor means engaging the peripheral surface of said inked die wheel for controlling the amount and distribution of ink on said die roller. Adjustment means are provided for mounting said impression roller, well and doctor means on said frame for lateral displacement relative to the longitudinal axis of said die wheel. The die wheel is preferably rotated by an idler motor when the segmenting means is stopped, registration means being provided to insure registration upon the restarting of the segmenting means, and therefore the web marking apparatus.

Accordingly, it is an object of this invention to provide a web marking apparatus adapted to impart indicia on a moving continuous web, said indicia being in registration with segments defined in said web by a segmenting means which operates on said web thereafter.

A further object of the invention is to provide a web marking apparatus which can be driven as a slave to a segmenting means to which it is connected with the die wheel of said apparatus rotating at a circumferential speed substantially equal to the circumferential speed of the segmenting wheel of said segmenting means.

Still another object of the invention is to provide a web marking apparatus wherein the die wheel is readily removable for substitution of die wheels selected from a group including die wheels of different diameters, the other components of said apparatus being adjustable to accommodate said die wheel of different diameter.

A further object of the invention is to provide a web marking apparatus which will maintain the registration between the indicia imparted thereby on a moving continuous web and the segments defined in said web by a segmenting means after the stopping and restarting of said segmenting means and web marking apparatus.

Still other objects and advantages of the invention will in part be obvious and will in part be apparent from the specification.

The invention accordingly comprises the features of construction, combinations of elements, and arrangement of parts which will be exemplified in the constructions hereinafter set forth, and the scope of the invention will be indicated in the claims.

BRIEF DESCRIPTION OF THE DRAWINGS

For a fuller understanding of the invention, reference is had to the following description taken in connection with the accompanying drawings, in which:

FIG. 1 is a schematic representation of the web marking apparatus in accordance with the invention, connected to a typical strip packaging system;

FIG. 2 is an enlarged elevational view taken along lines 2—2 of FIG. 1 showing a package formed by said strip packaging system;

FIG. 3 is a schematic representation of the web marking apparatus in accordance with the invention, connected to a typical rotary knife system;

FIG. 4 is a plan view of the web marking apparatus according to the invention with portions broken away;

FIG. 5 is a longitudinal sectional view of the web marking apparatus of FIG. 4;

FIG. 6 is a longitudinal sectional view of the web marking apparatus of FIG. 4 disposed to accommodate a die wheel of increased diameter;

FIG. 7 is a fragmented elevational view taken along lines 7—7 of FIG. 4;

FIG. 8 is a fragmented enlarged sectional view taken along lines 8—8 of FIG. 5;

FIG. 9 is a fragmented perspective view of the drive means for the web marking apparatus according to the invention;

FIG. 10 is a fragmented elevational view taken along lines 10—10 of FIG. 4;

FIG. 11 is a sectional view taken along lines 11—11 of FIG. 9;

FIG. 12 is a sectional view taken along lines 12—12 of FIG. 11;

FIG. 13 is an exploded perspective view of the ink well and adjusting means therefor of the web marking apparatus according to the invention; and

FIGS. 14 and 15 are sectional views taken along lines 14—14 and 15—15 respectively of FIG. 4.

DESCRIPTION OF THE PREFERRED EMBODIMENTS

Referring now to FIG. 1, the web marking apparatus 10 according to the invention is shown schematically, incorporated into a typical strip packaging system 12 also schematically depicted. Said strip packaging system includes rolls 14 and 16 of a continuous web of a thermoplastic packaging material such as polyethylene or a laminate formed from layers of polyethylene and aluminum foil or polyethylene, aluminum foil and paper. Webs 18 and 20 are drawn respectively from rolls 14 and 16 around guide rollers 22 in the direction of arrows 24. The two webs are brought together at sealing rollers 26, at which point articles 28 to be packaged are sequentially delivered at the output of the throat of funnel 30. One or both of sealing rollers 26 have circumferentially spaced cavities 32 formed in the periphery thereof to form a clearance to receive articles 28 as they are sequentially fed thereto by means not shown. One or both of said rollers are heated to seal the thermoplastic material along the periphery of each cavity to define a plurality of segments in said joined webs, each defining a package 33 containing one or more of articles 28.

Sealing rollers 26 are coordinately driven by means not shown in opposite directions as depicted by arrows 27 and rotate in pressing engagement to draw webs 18 and 20 therebetween and to effect a proper seal. Each package 33 is defined by the seal between webs 18 and 20 which extend along the periphery thereof. Sealing rollers 26 can be adapted to score or weaken the zones 34 of the segmented web between adjacent packages 33 to facilitate separation of the individual packages from each other.

For many applications, it is desirable to mark each package 33 with an indicia 35 indicating the lot, the date packaged, the product contained therein or other identifying information. This marking must be accomplished before the sealing of the webs by rollers 26 in order to avoid damaging articles 28. Accordingly, web marking apparatus 10 is provided for marking the face of web 20 which will form an outer surface of packages 33. Said web marking apparatus includes a rotating die wheel 36 for imparting the indicia to web 20, a rotating impression roller 38 for pressingly engaging said web against said rotating die wheel and well 40 carrying ink 42, for supplying ink to said die wheel which extends therein. Ink supply container 44 is provided pivotably mounted on conduit 46 for supplying ink to and draining ink from well 40 in a manner to be described below. Die wheel 36 rotates in the direction of arrow 37 to mark web 20 as it passes between said die wheel and impression rollers 38. Said impression roller is preferably freely rotatable and rotates in the direction of arrow 39 in response to the rotation of die wheel 36 and the passage of web 20 thereby.

It is critical to proper registration between the indicia 35 and packages 33, that said indicia be disposed in predetermined locations on web 20 when said web is joined with web 18 by sealing rollers 26 to define said packages. Such proper registration is accomplished by providing a connecting means, schematically represented by dashed lines 48, interconnecting die wheel 36 and one of said sealing wheels 26 to drive said die wheel in response to the rotation of said sealing wheel. Further, if the diameter of die wheel 36 and the mechanism of connecting means 48 are selected whereby said die wheel is rotated at a circumferential speed substantially equal to the circumferential speed of said sealing wheels, registration of indicia 35 and packages 33 is assured.

In one embodiment of the foregoing arrangement particularly adapted to produce an extremely flexible system, the mechanism of connecting means 48 is selected to drive die wheel 36 at substantially the same angular velocity as sealing wheels 26. In this embodiment the diameter of die wheel 36 is selected to substantially equal the diameter of sealing wheel 26, so that the circumferential speed of said die and sealing wheels are substantially equal. If sealing wheel 26 were formed with six spaced cavities 32 in its peripheral surface, die wheel 36 would preferably be formed with six circumferentially spaced printing means on its peripheral surface adapted to impart indicia 35 to web 20.

The flexibility of the foregoing arrangement rests in the fact that when strip packaging system 12 is modified to produce packages of different sizes or design by substituting new sealing wheels 26, registration of the indicia with the new packages is assured by merely replacing die wheel 36 with a die wheel specifically adapted for registration with said new packages. To this end, the web marking means according to the invention is specifically adapted to permit the substitution of a plurality of die wheels of various diameters.

Since web marking means 10 functions as a slave to sealing wheels 26 and only operates during the operation thereof, the entire system may be started and stopped without disturbing registration. Further, the angular velocity of the sealing wheels and therefore the rate of production of the system may be varied without making separate adjustments to marking means 10.

A further application of the web marking apparatus according to the invention is shown in FIG. 3. The rotary knife system 50 depicted schematically therein includes roll 52 of a continuous web of material 54 which is drawn therefrom in the direction of arrows 55 through guide rollers 56 to rotary knife wheels 58 and 60. Wheel 60 is provided with blade 62 adapted to cooperate with notch 64 in wheel 58 to divide web 54 into a plurality of segments of uniform length. These segments could then be used for packaging articles and containers by means of a conventional wrapping machine not shown. Said rotary knife wheels are driven in opposite directions (wheel 62 in the direction of arrow 63 and wheel 64 in the direction of arrow 65) by means not shown and are normally in pressing engagement to drive web 54 therebetween. As in the case of the strip packaging system, indicia are to be imparted at predetermined locations on each of said segments and accordingly, a web marking apparatus 10 is shown schematically connected to said rotary knife system. Web marking apparatus 10 is substantially identical to the web marking apparatus described in connection with FIG. 1. The die wheel 36 thereof is driven as a slave to knife rollers 58 and 60 by means of connecting means 66 shown schematically by dashed lines. According to the invention, the mechanism of connecting means 66 and the diameter of die wheel 36 are selected, whereby the circumferential speed of said die wheel is substantially equal to the circumferential speed of said knife wheels.

While the web marking apparatus, according to the invention, is shown connected to typical strip packaging and rotary knife systems, it is apparent that said apparatus

may be applied to any system wherein indicia must be imparted to a continuous web for registration with discrete segments defined in said web by a segmenting means having a rotatable segmenting wheel. Further, while one typical strip packaging system and one typical rotary knife system are described herein, the web marking arrangement, according to the invention, is applicable to all of such systems having a rotatable segmenting wheel for operating on said web.

Turning now to FIGS. 4-15, a specific embodiment of the web marking apparatus, according to the invention, is shown.

This web marking apparatus is adapted to permit the rapid substitution of any die wheel selected from a group comprising die wheels of different diameters. Such substitution is required to match the die wheel to the segmenting wheel of the segmenting means to which the apparatus is connected, thereby insuring proper registration between the markings on the web and the segments into which it is divided. Said apparatus is provided with a frame 70 for supporting the various components thereof. Die wheel 36 is mounted for rotation on shaft 72, which is rotatably supported on frame 70 by split bearings 74. Said split bearings are retained within the frame by plate 76, which is removably secured to said frame by means of screws 78. Die wheel 36 may be readily removed from frame 70 by removing screws 78, plates 76 and the top half 80 of split bearing 74.

Impression roller 38 is mounted on shaft 82 for rotation therewith, said shaft being mounted at its ends in sockets formed in blocks 84 for free rotation therein. As best shown in FIGS. 5 and 6, blocks 84 are mounted for longitudinal displacement within a channel defined by angle bars 86 secured to frame 70 by means of screws 87. The displacement of said blocks laterally displaces impression roller 38 relative to the longitudinal axis of die wheel 36, as defined by shaft 72. Each of blocks 84 are formed with a longitudinal threaded aperture 88. A threaded bolt 90 is disposed within each of said apertures 88, said apertures being adapted to accommodate varying lengths of their respective threaded bolts. A lock nut 92 is disposed about each bolt 90 to retain said bolt in predetermined positions wherein a predetermined length thereof extends within the corresponding aperture 88. Each bolt 90 extends through an aperture 94 in frame 70 and is longitudinally displaceable therethrough. The head 96 of each bolt 90 defines a cam follower which cooperates with a cam 98 fixed to shaft 100. Each bolt head 96 is biased against its respective cam 98 by a spring 102, which is seated between said head and the portion of frame 70 in the region of its respective aperture 94.

In order to accommodate the particular die wheel selected from the group having different diameters, impression roller 38 must be laterally displaced relative to shaft 72 to a position at which it pressingly engages web 20 against said die wheel. By way of example, FIG. 6 shows impression roller 38 laterally displaced away from shaft 72 to accommodate a new die wheel 36' of increased diameter substituted for die wheel 36 (FIGS. 4 and 5). This lateral displacement of impression roller 38 is accomplished by threading a greater length of bolts 90 within their requested apertures 88 to longitudinally displace blocks 84, carrying therewith shaft 82 and impression roller 38. Lock nuts 92 are released to permit said lateral displacement, and after positioning, are tightened to lock said impression roller in the new location. In order to insure uniform printing, two bolts are disposed within their corresponding apertures so that shaft 82 is parallel to shaft 72.

Cams 98 and shaft 100 are part of a mechanism operated by pneumatic or hydraulic cylinder 104, adapted to disengage impression roller 38 from die wheel 36, when the segmenting means is brought to a halt. Web 20 is positioned to be carried by said impression roller into and out of engagement with said die wheel when said

mechanism is activated. This arrangement permits die wheel 36 to be rotated by an idler motor, during periods that the segmenting means is stopped, without producing a smudged imprint on web 20, which is also stopped. The 5 idling of said die wheel prevents ink disposed thereon, and in well 40, from drying out. Cylinder 104 is operated by fluid lines 105 and 106 which are connected to a pump (not shown) operated by a microswitch (not shown). Said microswitch is adapted to detect the starting and 10 stopping of the rotation of the segmenting wheels, such as sealing wheels 26 or rotary knife wheels 58 and 60. As best shown in FIG. 7, piston 108 of cylinder 104 is hingedly connected to one end of lever 110, which is fixed to shaft 100 for the rotation thereof in response to the 15 longitudinal displacement of said piston. Cylinder 104 is mounted to frame 70 by means of yoke 112, pin 113 and bracket 114.

Web marking apparatus 10 is shown disposed in the operative position where indicia are being marked on web 20. In this position, the fluid is applied to line 105 20 to hold the piston in position. When the microswitch detects that the segmenting means has stopped, the fluid is applied to line 106 to longitudinally displace piston 108 to the left, as shown in FIG. 4, thereby rotating shaft 100 to present a portion of cams 98, having a smaller diameter to the corresponding head 96 of bolts 90. Springs 102 bias said bolt heads against said cams, causing the displacement of blocks 84, which in turn laterally displaces impression roller 38 out of engagement with die wheel 36. When the segmenting means recommences operation, the process is reversed with fluid being applied to line 105 and impression roller 38 being rapidly displaced back into engagement with said die wheel. The lateral displacement of impression wheel 38 carries web 20 into and out of engagement with die wheel 36.

Reference is now had to FIGS. 4, 5, 8 and 13 which more particularly show the arrangement for mounting and displacing ink well 40. Well 40 includes a bottom wall 116, defined by a quadrant of a cylinder of a diameter larger than that of the largest die wheel adapted to be received therein and end walls 118 for retaining ink 42. There is little or no projection of the forward lip 119 of said well beyond the forward edge of die wheel 36, thereby providing clearance for the substantially vertically extending web 20 passing thereby. The rear lip 120 of said well extends above said forward lip to catch any excess ink removed from the roller by a doctor blade 122. This raised rear lip also serves as a splash guard to catch ink which may be splashed from newly inked portions of die wheel 36.

The bottom wall of well 40 is provided with an aperture 124 to which is connected conduit 46. Secured to the opposite end of said conduit by means of screw 127 and washer 128 is mounting block 130. Said mounting block is provided with a bore 132 adapted to receive ink supply 55 container 44 therein and to provide communication between said container and apertures 134 extending through the wall of conduit 46. Mounting block 130 is adapted to pivot about the circumference of conduit 46, carrying ink supply container 44 therewith. Said conduit is provided with a plurality of apertures 134, spaced about its circumference in the region of bore 132, whereby ink may be continuously supplied to well 40 when the ink supply container is in the upper position and may be drained from said well when the container is in the lower position. Sealing rings 135 are provided on both sides of bore 65 132 in engagement with conduit 46 to prevent the leakage of ink between said conduit and mounting block 130. Reference is had to United States Letters Pat. No. 3,318,238 issued on May 9, 1967, for a detailed description 70 of the structure and function of this arrangement for supplying and draining ink from a well or fountain.

A portion 136, of the outer surface of conduit 46 is threaded and knurled lock nut 138 is disposed thereon. The conduit extends through a vertically extending slot 75 140 in frame 70 and the well and conduit assembly is held

in place, in part, by lock nut 138 engaging against frame 70. Well 40 is further supported by means of guide blocks 142 formed with an inclined channel 144 therein. Each of said guide blocks is secured to the inside surface of frame 70 at opposite sides of said well. A finger 146 is adapted to ride in said inclined channel. A threaded bolt 148 extends through a correspondingly threaded aperture 149 in each block 142, into channels 144. Said bolts determine the length of said channels, thereby positioning fingers 146 therein. Tightening lock nut 138 draws fingers 146 up the inclined channel 144 until said fingers engage the end of bolts 148. Referring again to FIG. 6, wherein a die wheel 36' of increased diameter is shown substituted for die wheel 36, it can be seen that well 40 is adjusted to accommodate said new die wheel by being displaced downwardly and forwardly along the line defined by inclined channels 144. Specifically, lock nut 138 is displaced toward mounting block 130 and bolts 138 are rotated so that a greater length of each extends into its corresponding inclined channel. The well and conduit assembly is locked in the new position by tightening lock nut 138 against frame 70 with conduit 46 disposed in a lower position within slot 140 and fingers 136 disposed in a lower position in channels 144 of guide blocks 142.

Die wheel 36 is preferably of the gravure type wherein the printing means consists of recesses in the surface of the plate shaped as letters, numerals or other indicia and adapted to receive ink therein as they pass through the bath of ink 42. After a portion of the peripheral surface of die wheel 36 leaves well 40, excess ink from the surface thereof is removed by doctor blade 122. The ink-laden recesses are then brought into contact with web 20 which is pressed thereagainst by impression roller 36 to deposit the ink on said web, thereby imparting the desired indicia thereon. Doctor blade 122 is preferably formed from a resilient material such as rubber. Said doctor blade is supported upon a U-shaped bracket 150, mounted on a reciprocating rod 152. The two arms 154, of bracket 150 are each formed with a slot 156. The ends 158 of doctor blade 122 are formed with a longitudinally extending threaded aperture 160 and are sized to extend into slot 156. Said doctor blade may be locked in any position along slot 156 by means of screws 162 which extend into correspondingly threaded apertures 160. Referring again to FIG. 6, die wheel 36' of increased diameter is shown disposed in the web marking apparatus according to the invention and doctor blade 122 is shown displaced laterally away from shaft 72 along slots 156 to accommodate said larger die wheel.

Bar 152, upon which bracket 150 is mounted, extends through apertures 164 in frame 70 and is supported therein by bearings 165. Retaining member 166 is secured to the outside wall of frame 60 about one of said apertures 164 to retain spring 168, the other end of which is received in a socket 167 in the end of said aperture. The other end, 169, of said rod serves as a cam follower and cooperates with cam surface 170 of wheel 172. Said cam surface is inclined from the vertical and bar 152 is biased thereagainst by spring 168. The bar thus reciprocates along its longitudinal axis in response to the rotation of wheel 172, carrying doctor blade 122 therewith to improve the action thereof.

The above-described arrangement of die wheel 36, impression roller 38, well 40 and doctor blade 122, provides an extremely flexible gravure printing arrangement, particularly adapted for application to segmenting means of the type also described above. Thus, the impression roller 38 is disposed on the side of die wheel 36 rather than above said die wheel, as in the known arrangements, to permit the ready removal and replacement of said die wheel by a die wheel selected from a group having a wide range of diameters. The impression roller, well and doctor blade are all displaceable relative to the longitudinal axis of die wheel 36, thereby permitting the substitution of said die wheels of various diameters. Further, well 40 is

specifically adapted so as not to interfere with the substantially vertically extending web 20 as it passes between said die wheel and said impression roller. The adjustment arrangements for the impression roller, well and doctor blade have been specifically designed so as not to interfere with the normal operation of the marking means, including the mechanism for displacing said impression roller into and out of engagement with said die wheel in response to the starting and stopping of said segmenting means, the reciprocal displacement of the doctor blade, and the ink feeding and draining arrangement for the well.

Turning now to FIGS. 4 and 9-12, the connecting and driving arrangement, according to the invention is shown. 15 Mounted on shaft 72, for the rotation of said shaft and die wheel 36, is gear 176. Wheel 172, having cam surface 174 for reciprocating bar 152, is mounted on frame 70 by means of stub axle 178. Said axle also serves as a pivot point for the hinged mounting, at one end thereof, of plate 180. A further stub axle 182 is rotatably mounted on the other end of said plate. Secured to stub axle 182 for rotation therewith, are gear 184, belt wheel 186 and sprocket wheel 188.

Gear 184 is in meshing engagement with gear 176 25 for driving gear 176 and die wheel 36. Belt wheel 187 is coupled to wheel 172 by endless belt 190 for the rotation of wheel 172 and the reciprocation of doctor blade 122. Plate 180 is locked against frame 70 with gears 184 and 176 in meshing engagement by screw 181 which 30 extends through a slot 183 in said plate. A spring 185 may be provided (FIG. 10) to bias said plate upwardly to maintain the meshing engagement of said gears and to counter the downward force caused by the interaction of said gears. This arrangement permits the replacement 35 of gear 184 by a gear selected from a group including gears of different diameters, plate 40 being pivoted to accommodate the substituted gears. In this manner, the gear ratio between gears 184 and 176 can be adjusted to change the angular velocity of die wheel 36 to maintain 40 the circumferential speed thereof at a value equal to that of the segmenting wheel after said segmenting wheel has been altered in some respect. This modification would be sufficient in certain circumstances without requiring the substitution of a new die wheel or could be made in addition to such substitution. Sprocket wheel 188 is connected to a further sprocket wheel 192 by a chain or 45 other connecting means shown schematically by dashed line 194. Sprocket wheel 192 is fixedly mounted on intermediate shaft 196 for rotation thereby and transmits the 50 rotation of said intermediate shaft to sprocket 188 for the driving of web marking apparatus 10.

In the arrangement according to the invention, said web marking apparatus is driven as a slave in response to the rotation of the segmenting wheel of the segmenting means to which it is connected. Specifically, sprocket wheel 198 is coupled to the segmenting wheel of said parent segmenting means as shown schematically by dashed lines 200 and is rotatively driven in response thereto.

60 The coupling could be directly to some element of the driving means for said segmenting means rather than to the segmenting wheel driven thereby. Such driving means element may rotate at the same angular velocity as said segmenting wheel or some predetermined proportion thereof. In the latter case, the arrangement connecting said element to said die wheel would be adapted to transform the angular velocity of said element to the angular velocity required to drive the die wheel according to the invention. Shaft 196 is journaled through sprocket wheel 198 to 65 permit the rotation of said shaft independent of said sprocket wheel, the driving force of sprocket wheel 198 being transmitted to sprocket wheel 192 through a registration arrangement 202 in a manner described below.

70 The foregoing arrangement is necessitated by the provision of idler motor 204 coupled to drive shaft 196 through

sprocket wheel 206 and an override clutch 210. The coupling arrangement between sprocket wheel 206 and override clutch 210 is shown schematically by dashed lines 208. Idler motor 204 is provided to rotate die wheel 36 during periods that the parent segmenting means is stopped to prevent the ink from drying out in the recesses of the gravure type die wheel or in the well. Idler motor 204 runs at a lower revolution per minute rate than the normal speed of the segmenting wheel, as transmitted to intermediate shaft 196 through sprocket wheels 192 and 198 and registration arrangement 202. The drive from said idler motor is applied directly to first clutch member 212 of said override clutch, said first clutch member being adapted for rotation independent of shaft 196. The second clutch member 214 of said override clutch is fixed to shaft 196 and is rotated therewith. During normal operation, shaft 196 is rotated at a relatively high speed by sprocket wheel 198 acting through registration means 202 and sprocket wheel 192. Override clutch 210 is adapted to permit relative rotation between said first and second clutch members whereby the rotation of intermediate shaft 196 is governed by the higher revolution per minute rate of the drive from the segmenting wheel rather than the lower speed of the continuously operating idler motor. However, when sprocket wheel 198 stops in response to the stopping of said segmenting means and is locked in place by the coupling arrangement 200, shaft 196 continues to rotate under the influence of the idler motor, the drive of which is transmitted thereto through override clutch 210. As described above, impression roller 38 is disengaged from the die wheel during this period, carrying web 20 with it.

Since die wheel 36 is continuously rotated by idler motor 204 during the period that the segmenting wheel is stopped, said die and segmenting wheels need not be in registration at the instant that said segmenting wheel is activated. Registration means 202 is interposed between said die and segmenting wheels to insure that said wheels are immediately brought into proper registration. Registration means 202 includes pin 216, extending normally from and secured to the side face of sprocket wheel 198, latch dog 218 pivotably mounted by means of pin 220 to the side face of sprocket wheel 192, and spring 224 fixed at one end to said side face of sprocket wheel 192 and adapted to bias latch dog 220 against intermediate shaft 196 to rotate same. The rotation of shaft 196 carries with it sprocket wheel 192 which is fixed thereto. As sprocket wheel 192 rotates, face 228 of latch dog 220 engages against fixed pin 216 and rides therewith once during each rotation to pivot said latch dog about pin 222 against the bias of spring 224, said spring returning said latch dog back into engagement with shaft 196 when pin 216 clears face 228. Upon the restarting of the segmenting wheel, registration is reestablished because pin 216 engages face 226 of said latch dog to override the idler motor only when sprocket wheels 192 and 198 are properly aligned relative to each other. Idler motor 204 could be coupled through an override clutch directly to shaft 72. In such an embodiment, said shaft would be journaled through gear 196 and registration means 200 would be interposed directly between said gear and said shaft, means being provided for mounting latch dog 220 on shaft 72 for pivoting relative thereto.

The foregoing drive and connecting arrangement, according to the invention insures that the web marking apparatus 10 is fully responsive to the rotation of the segmenting wheel of the segmenting means to which said web marking apparatus is connected, while insuring continued registration between the indicia imprinted on web 20 and the segments into which said web is later divided. Further, said driving and connecting arrangement provides a means for continuously rotating die wheel 36 while the segmenting means is stopped to keep the ink stirring and to insure that the ink on the die wheel does not dry out.

Web marking apparatus 10 is particularly adapted for

connection to a segmenting means and for operation as a slave to the segmenting wheel thereof. Further, the above-described driving and connecting arrangement and said web marking apparatus are particularly adapted for driving a die wheel selected from a group of the wheels of different diameters at a circumferential speed substantially equal to the circumferential speed of the segmenting wheel without regard to variations in the angular velocity of said segmenting wheel. Particularly, the provision of means for readily removing die wheel 36 for the replacement thereof by a die wheel of a different diameter; the adjustment means for the displacement of impression roller 38, well 40 and doctor blade 122; and the hinged mounting of plate 180 carrying gear 184 on frame 20 to permit the substitution of gears of different diameters for gear 176, constitute substantial advances over the prior art.

It will thus be seen that the objects set forth above, among those made apparent from the preceding description, are efficiently attained and, since certain changes may be made in the above constructions without departing from the spirit and scope of the invention, it is intended that all matter contained in the above description or shown in the accompanying drawings, shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

What is claimed is:

1. Apparatus for marking a moving continuous web, said web to be operated on by segmenting means having a rotatable segmenting wheel engaging said web for defining a plurality of segments in said marked web, and driving means for rotating said segmenting wheel, which comprises marking means having a rotatable die wheel engaging said moving web for marking same; connecting means operably connecting said driving means and said die wheel for rotating said die wheel at a circumferential speed substantially equal to the circumferential speed of said segmenting wheel, said markings being disposed in predetermined locations on said web for registration with said segments; an override clutch means; and an idler motor coupled to said die wheel through said override clutch means; said override clutch means being adapted to transmit the rotative drive of said idler motor to said die wheel when said segmenting wheel is stopped, and to permit said die wheel to rotate in response to said driving means when said segmenting wheel is rotating, said connecting means including registration means interposed between said die wheel and said driving means for coupling said die wheel and driving means during the rotation of said segmenting wheel, permitting the rotation of said die wheel in response to said idler motor when said segmenting wheel is stopped and returning said markings to registration with said segments by coupling said die wheel and driving means upon the initial rotation of said segmenting wheel only when said die and segmenting wheels are aligned.

2. Web marking apparatus, as recited in claim 1, wherein said driving and connecting means rotate said segmenting wheel and said die wheel at substantially the same angular velocity, said segmenting and die wheels having substantially identical diameters.

3. Web marking apparatus, as recited in claim 1, wherein said segmenting means comprises a strip packaging system, said segmenting wheel being a sealing wheel.

4. Web marking apparatus, as recited in claim 1, wherein said segmenting means comprises a rotary knife system, said segmenting means comprising a rotary knife wheel.

5. Web marking apparatus, as recited in claim 1, wherein said marking means includes a frame; a shaft rotatably mounted on said frame, said die wheel being mounted on said shaft for rotation therewith; and a driven means coupled to said connecting means for rotation in

response to said driving means, said driven means being removably mounted on said shaft for rotation of said shaft and die wheel, the portion of said connecting means coupled to said driven means being displaceable relative to said driven means to accommodate a driven means selected from a group including driven means of different diameters.

6. Apparatus for marking a continuous web as recited in claim 1, wherein said marking means includes a frame; mounting means for removably supporting said die wheel on said frame for substitution of a die wheel selected from a group including die wheels of different diameters, said mounting means being adapted to permit removal of said die wheel in a substantially upward direction; a well for carrying ink, a portion of said die wheel extending within said well for inking the peripheral surface thereof; doctor means engaging the peripheral surface of said inked die wheel for controlling the amount and distribution of ink thereon; a rotatable impression roller pressingly engaging said moving web against said rotatable die wheel; and adjustment means for mounting said well, doctor means and impression roller on said frame for lateral displacement relative to the axis of said die wheel to accommodate a die wheel selected from said group thereof.

7. Web marking apparatus as recited in claim 1, wherein said registration means includes a shaft coupled to said clutch means for rotation by said idler motor and to said die wheel for rotation thereof in response to either said idler motor or said driving means; drive wheel means having said shaft journaled therethrough and having a pin extending from a side thereof; a latch dog mounted for rotation with said shaft and pivotable into and out of en-

gagement therewith; and spring means for biasing said pivotably mounted latch dog against said shaft, said latch dog having a first surface engageable by said pin for rotatably driving said latch dog and shaft to rotate said die wheel in response to said driving means, and a second surface engageable by said pin to pivot said latch dog out of engagement with said shaft to provide clearance for said pin when said drive wheel means is stopped in response to the stopping of said segmenting wheel while said shaft and latch dog continues to rotate in response to said idler motor.
